CLAIM

The ornamental design for a two-tier table, as shown and described.

DESCRIPTION

FIG. 1 is a perspective view favoring the rear.

FIG. 2 is a perspective view favoring the front.

FIG. 3 is a top view.

FIG. 4 is a front view.

FIG. 5 is a side view, both side being identical; and,

FIG. 6 is a rear view.

The shape generally represents a table section about the height of a kitchen table and a leg rest section about the height of an ottoman all on the same structure along with some shelving space.
